UNITED STATES PATENT OFFICE.

THOMAS S. WHEATCROFT, OF RUSH, PENNSYLVANIA.

COIN-CONTROLLED VENDING-MACHINE.

SPECIFICATION forming part of Letters Patent No. 674,049, dated May 14, 1901.

Application filed March 16, 1899. Renewed October 17, 1900. Serial No. 33,402. (No model.)

To all whom it may concern:

Be it known that I, THOMAS S. WHEATCROFT, a citizen of the United States, residing at Rush, in the county of Susquehanna and State of Pennsylvania, have invented certain new and useful Improvements in Coin-Controlled Vending-Machines; and I do hereby declare the following to be a full, clear, and exact description of the invention, such as will enable others skilled in the art to which it appertains to make and use the same.

This invention relates to vending-machines of the coin-controlled class and particular type known as "article-delivery," and wherein articles, materials, or substances are fed in bulk to the mechanism, automatically apportioned thereby in predetermined quantities, deposited in individual bags or other receptacles separately fed into receptive position, and delivered to the purchaser in package.

In addition to the foregoing general statement this invention includes many other salient characteristics, and among which may be mentioned the absolute prevention of fraudulent manipulation of the machine embodying the same, and which is an important factor in its complete efficiency. It is arranged to stop and repel lead slugs, tokens, washers, or any analogous device other than the proper coin prescribed for its operation. Also coins intentionally or otherwise dropped in the slot of smaller dimension and unlike that the machine is adjusted or constructed to receive will be returned instantly to the person inserting them, and loss of same or intention to operate therewith is obviated. Furthermore, if the required coin be inserted and a simultaneous effort made to operate the machine and before the coin reaches an actuating position an immediate resistance will ensue and an after automatic resetting and regular deposit of the coin will take place to permit a subsequent full operation of the starting mechanism and a delivery of the vended article. By this means the purchaser never sustains a loss by failure of the mechanism to operatively respond and is invariably accorded a return for the necessary regular coin deposit. An attempt to obtain a repeated or multiple vendition by the use of a single coin will be frustrated also, and the

machine can be left unguarded without risk of loss from such nefarious practice.

The relative use of a preferred form of registering attachment is a potent feature in that it not only accurately records and indicates the sum-total of the deposited coin, but also correspondingly and unerringly discloses the exact number of vended packages, articles, or portions, as the operation is such that the total deposited coins must uniformly tally with the sales automatically made, and thus advantageously and effectively exemplify the fulfilment of an agreement as to the distribution of advertising matter applied to or carried by the packages or articles regularly taken from the machine.

The preceding statement expresses but a few of the more important advantages of the invention, and these broadly contemplate many other contributory structural conveniences which will become apparent hereinafter, and the mechanism and means which will be presently explained are intended to be considered as including all equivalent or analogous substitutes, and the form and parts illustrated are solely for the purpose of demonstrating a practicable embodiment of what is believed to be a simple structure for accurately disclosing the operation.

In the accompanying drawings, Figure 1 is a perspective view of the cabinet or inclosure of the vending-machine embodying the invention and attachments incidental thereto. Fig. 2 is a side elevation of the operating mechanism removed from the cabinet or inclosure and in normal position. Fig. 3 is a similar view showing the parts in a different or operating position. Fig. 4 is a similar view of the opposite part of the mechanism and in normal position. Fig. 5 is a central longitudinal vertical section of the mechanism shown in normal position. Fig. 6 is a sectional elevation looking from the rear. Fig. 7 is a detail perspective view of parts of the device, showing the manner of opening and filling a bag. Fig. 8 is a top plan view of the combined measuring and holding compartment shown shut off and the mechanism used in conjunction therewith. Fig. 9 is a transverse section of the upper rear part of a portion of the measuring and holding compartment, showing part of the mechanism for

operating the cut-off. Fig. 10 is a detail perspective view of a part of the cut-off-operating mechanism. Fig. 11 is a similar view of another part of the cut-off-operating mechanism. Fig. 12 is a detail perspective view of a movable scoop. Fig. 13 is a longitudinal vertical section through one side of the machine looking toward the starting mechanism from a side opposite to that shown by Fig. 2. Figs. 14 and 15 are elevations of different parts of the mechanism. Fig. 16 is a detail perspective view of the receiving end of the mouth of the cash-box. Fig. 17 is a detail plan view of a part of the starting mechanism, showing locking devices therefor. Fig. 17^a is a detail perspective view of a part of the scoop, showing a variation in the form of a part thereof. Fig. 18 is a sectional view of a modified form of delivery-outlet. Fig. 19 is a detail perspective view of a modified form of bag holding and feeding device. Fig. 20 is a longitudinal vertical section of the device shown by Fig. 19. Fig. 21 is a front view of the slotway. Fig. 22 is a detail transverse vertical section of the lower portion of the mechanism looking toward the front. Fig. 23 is a perspective view of the shield-plate. Fig. 24 is a detail view in perspective of the bifurcated plate. Fig. 25 is a perspective view of the wiper.

Referring to the drawings, wherein similar numerals are employed to indicate corresponding parts in the several views, the numeral 1 designates an inclosure of suitable form and dimension, and therein the several mechanisms and devices are relatively positioned for conjoint and individual operation and in the main attached to a vertical face-support 2.

For convenience in locating and alluding to the several mechanisms they will be described under separate heads, such as "Starting mechanism," "Vending mechanism," "Coin mechanism," "Registering mechanism," and "Display advertising mechanism."

45 *Starting mechanism.*—From the lower part of one side of the face-support 2 an arm 3 extends rearward and terminates in an upturned end 4, having a grooved roller 5 bearing therein and a rear vertical bifurcate plate 6. On 50 the same side of the support 2, above arm 3, brackets 7 are secured and have a channeled plate 8, also projecting rearward therefrom and provided with guides 9 and ratchet-bars 10, having teeth thereon a part of their length 55 and oppositely disposed. The plate 8 is formed with a central slot 11, and 12 is a pull-bar movable on the guides 9 and out through the support 2. Exterior of the said support 2 the bar 12 has a grip or handle 13 on its 60 outer end and forms a stop to limit the automatic inward return movement derived from means presently set forth and also serve to accurately dispose the same in a normal position of rest for repetitive operations. The 65 rear end of the bar 12 has a vertical slot 14 and a coin-receiver 15, formed with grooves 16 in opposite sides to slidably engage the

guides 9. Lugs or projections 17 extend inward toward each other at the rear part of the receiver and have a longitudinal opening 18 between them, and also between the front limiting ends of said lugs or projections and the rear end of the bar 12 a transverse opening 19 exists and first receives the coin and retains it in upright position until cleared from the said bar. The upper faces of the lugs or projections 17 are formed with recesses 20, and these, together with the slot 18, are to correlative receive contributing mechanism carried by the primal coin-controlling device. 80 On one side of the receiver 15 a pin 21 projects laterally, and on the opposite side, preferably at the point of juncture of the bar 12 and said receiver, a wiper 22 is located and consists of a slotted head 23, pivotally connected to said parts and having a rounded or analogous stud 24, extending inward. This wiper has a spring 25 secured thereto and to a rear adjacent part of the receiver and is positively prevented from having a rearward movement by abutting against a shoulder 26, formed by the projection of the receiver, but has an easy forward swing against the retractile effort of said spring 25, which tends always to restore it to a normal position. To 95 automatically redraw the bar 12 inwardly and normally position it after operation, springs 27 of suitable tension are attached to the rear upper part of the receiver 15 and to the arms of the bifurcate plate 6. The bar 12 can never be operated until a required coin has been regularly disposed in actuating relation thereto, and to guard against tampering with the machine a lock is employed and consists of an irregular yoke 28, pivotally attached to 100 the outer edge of the plate 8. The upper arm 29 of said yoke is shorter than the lower arm 30 and has an inwardly-projecting nose 31, normally resting in a semicircular recess 32 in the adjacent edge of said plate 8, and forms a stop for engagement with a shoulder 33 of the receiver 15 on that side. A curved cam projection 34 extends inwardly and forwardly from the lower arm 30 of the yoke and lies in the path of movement of a part hereinafter set forth for automatically releasing the lock at the proper time and under regular conditions. The nose 31 is continuously projected inward by a spring 35, bearing against an outer part of the yoke, and the latter is thereby always maintained in a sensitive locking position. A shaft 36 has bearing in the arm 3 at a suitable distance from the support 2 and also in another arm 37 at the opposite side of the mechanism. On a 115 portion of this shaft projecting out from arm 3 the lower end of a starting-lever 38 has rotation, and at the upper end of said lever is a finger 39, which moves in the slot 11 of the plate 8, and the bar 12 is cleared therefrom by means of the slot 14, into which said finger also projects for a time. The piston of an air-cushion 40 is movably connected to the lever 38 below the finger 39 by a rod 41, said

cushion being held by the upward-extending part 4 of the arm 3 and serves to ease the return movement of the said lever. Also attached to the lever above the point of engagement of the rod 41 is the front end of a cord or analogous device 42, which passes rearward over the grooved roller 5 and has a weight 43 secured to its depending end. From the outer side of the lever, just below the finger, a headed stud or similar device 44 projects and bears against the cam projection 34 on the lower arm 30 of the locking-yoke 28, the said cam projection being in such relative position to the stud that an outward swing of the lever will cause the yoke to be forced outwardly and gradually withdraw the nose 31 in a lateral direction from a locking position.

On the inner side of the lever 38 an actuating-dog 45 is gravitatingly attached and has a depending lug 46. The pin or bolt 47, on which the dog 45 is mounted, extends inwardly a sufficient distance for operating other mechanism hereinafter explained, and the lug 46 is located at a predetermined distance from the pin or bolt 47. The dog rearward from the lug 46 is sufficiently long and so shaped as to bear upon and easily move over a curved contact-head 48, supported by an upright from the arm 3. On the shaft 36, just inside the arm 3, a hub 49 is fixed and has a sector-cam 50 with a curved edge 51 and of less radial projection than the head 48, and with the front normally vertical edge 52 thereof the lug 46 is adapted to engage when the lever 38 is swung or moved far enough forward. The hub 49 also has a crank-arm 53 projecting therefrom in an upward and rearward oblique direction, and on an opposite portion of the shaft 36 a similarly-positioned crank-arm 54 is made fast. These crank-arms are attached to other mechanism, which will be subsequently described.

An arm 55 is attached to the lower part of lever 38 and projects forward and downward, and from the free end a rod 56 extends inward and carries an antifrictional grooved bearing-roller 57 on its free end. The arm 55 moves gradually and obviously simultaneously with the lever 38 and serves to open certain mechanism controlling the final delivery of the vended article or material.

The devices thus far disclosed actually control the starting of the operation of the feeding and the vending mechanism, including the apportioning or separation, disposition and delivery devices, and in part, at least, is automatic. So far as the purchaser is concerned the only act on his part necessary to set in motion the various independent devices will be the regular deposit of the prescribed coin and a withdrawal of the bar 12. As soon as the coin becomes positioned in the transverse opening 19 the purchaser can pull out the said bar 12 and the coin is drawn upright lengthwise of the plate 8. The coin is first brought in contact with the rear side of

the finger 39 on the upper end of the lever 38, and the latter is gradually pulled forwardly against the stress of the weight 43 until a full limit is reached, when the coin will pass into the upper part of a coin-chute 58, located against the adjacent inner part of support 2, and continuing down to the lower end of the latter, where it can be seen through a glass-covered sight-opening 59 in the support, and thence into a cash-receptacle of a form hereinafter explained. The pressure of the coin during the foregoing operation remains constant, owing to the rear retention thereof afforded by the lugs or projections 17 of the receiver 15, and as soon as the coin passes into the chute the bar 12 will have been pulled out to its full limit and the purchaser, appreciating the resistance as a notification, will let go, and the springs 27 will retract the bar into normal position. It will be understood, however, that the time of release for the purpose of the return of the bar does not in the least affect the operation, as the mechanism is set in motion at the time of deposit of the coin in the chute 58 or momentarily thereafter, and thus the purchaser has no control whatever over the operation of the several mechanisms. At the exact time that the finger 39 and arm 29 become disengaged the dog 45, which has also been gradually drawn forward, reaches such a point relatively to the cam 50 that it drops down and the lug 46 becomes positioned against the vertical edge 52 of said cam. The weight 43, which is sufficiently heavy to overcome the resistance of all the mechanism it is arranged to control, now draws the lever 38 rearward in a steady and regular manner, owing to the air-cushion 40. While the said lever is moving toward a normal position, as stated, the lug 46 is pushing the cam 50 over toward the rear and rotating the shaft 36 and lowering the crank-arms 53 and 54. During this time the lower portion of the dog will be riding over the contact-head 48 and the lug 46 thereby gradually raised as the lever 38 comes toward said head and until the said dog is entirely clear of and finally rests in inert condition on the curved edge 51 of the cam. The lower arm 55 is also gradually moved downwardly and slightly rearwardly by the advance of the lever 38, and the roller 57, carried by the rod 56, completes its work just at the time the said lever loses its radius and is automatically reset by the rearward movement of the lever.

Should a dishonest purchaser endeavor to obtain a dual or multiple vendition by the use of a single coin and by attempting to suddenly jerk or pulsate the bar 12, his efforts will be completely defeated, as the coin is so disposed when in opening 19 as to have diametrically opposite portions thereof engage the resisting faces or projections of the ratchet-bars 10, which stand forward, and after the bar 12 is drawn forward partially it cannot be returned rearward, and any sud-

den forward jerk will only lock it step by step in further-distended position and must be entirely drawn out to deliver the coin to chute 58 before its return is permitted and the vending mechanism operated.

The coin-operated mechanism being intimately associated with the vending mechanism is described in detail to enable a clear understanding of the operation and construction of the machine being obtained, and while said coin-operated mechanism is not claimed specifically herein it is not my intention to abandon the same.

Vending mechanism.—On the upper rear portion of the support 2 an inclosing box or casing 60 is located and has an open top and bottom and a rear downwardly-deflected bottom portion 61 to assist in more effectively carrying out the function of the devices operating thereon. This box or casing is disposed in the main behind an elongated glass panel 62 to clearly exteriorly display the movements of the parts, and thus mechanically explain the several operations attending the preparation of the vended article or material to the purchaser and gratify a naturally inquisitive disposition with benefit to the favorable indorsement of the machine. On the rear upper part of the box or casing 60 are bearings 63, suitably spaced apart, and in opposite sides of the said box or casing are vertical slots 64 in transverse alinement. The front side of the box or casing is closed by the adjacent parts of the support 2 and the panel 62, and the front edges for a portion of their length are formed with guide-slots 65, and the rear closed side 66 has an upper opening 67, adapted to be covered and provide for access to the mechanism to change or vary the adjustment. The lower portions of the bearings 63 have a rock-shaft 68 mounted therein, and to one end outside of one bearing a crank-arm 69 is fixed and extends forwardly and upwardly. On the other end of said rock-shaft 45 an arm 70 is fastened in such manner as to move therewith and has a counterpoise-weight 71 secured thereto and shiftable to vary the rapidity or sensitiveness of movement of parts controlled thereby. On the opposite end of the rock-shaft from that to which said weight 71 is attached a crank-arm 72 is also made fast and sets in a normal position similar to crank-arm 69. Intermediate the length and to the outer sides of the crank-arms 69 and 72 the upper ends of connecting-bars or analogous devices 73 and 74 are movably attached and also in like manner to the ends of crank-arms 54 and 53 on shaft 36, respectively on the outer and the inner sides of the latter crank-arms to avoid interference of the working parts. To the front ends of the crank-arms 69 and 72 depending links 76 and 75 are applied and have a free movement, and the lower ends of the same are swiveled on lateral guide-trunnions 77 of a scoop 78, operating in the box or casing 60. These trunnions regularly slide in the slots 64 and have antifrictional rollers 79

thereon for obvious reasons. This scoop is preferably of the form shown by Fig. 12 and has a closed front plate 80 and opposite angular sides 81, each of a similar contour and entirely open at the top and rear. The said sides have the upper rear edges straight for a portion of their length and then gradually and regularly incline to the front plate 80 and are intended to move close to the rear side 66 of the box or casing 60 for a time and insure such desired operation in view of a necessary initial normal disposition of the scoop at an angle to attain the several predetermined continuous functions thereof. The lower end of plate 80 is projected in the form of a curved edge lip 82, and the upper end 83 is extended beyond the upper terminations of the sides 81. The trunnions 77 are secured to the sides 81 near the top rear portion thereof, and to the upper extended end 83 a rod or analogous device 84 is fastened and sheathed, as at 85, to prevent lodgment thereon of the vended articles or materials or passage thereof between said sheathing and the part of the elongated panel 62 and support 2, against which said part of the scoop has close movement. The opposite ends of the rod or analogous device 84 are projected beyond the 95 sides 81 and form trunnions 86, which are movable in the guide-slots 65 at the front of the box or casing 60 and have antifrictional rollers 87 thereon to ease their sliding operation and avoid wear on contiguous engaged 100 surfaces. The sides 81 have slots 88 in their lower portions arranged parallel with the edges thereof, and above said slots the edges are cut away, as at 89, to reduce the frictional drag on the rear side of the box or casing 60 during the movement of the scoop 78 therein. The upper front parts of the sides 81 also have inclined slots 90 therein, which are parallel with the plate 80, and both sets of slots 88 and 90 coöperate with opposite 110 alined pairs of studs 91 and 92, working freely in front and rear openings 93 and 94 in the sides of said box or casing. The front inner ends of the studs project into the box or casing and are rounded, and the pair 91 are at a 115 higher elevation than the rear pair 92, and each stud is attached to the free end of a flat or other suitable spring 95, secured at an opposite portion to the exterior of the said box or casing and operate to normally press the 120 studs inwardly. These studs 91 and 92 engage the respective slots 90 and 88 in the sides 81 of the scoop at regular intervals and during certain periods to maintain a temporary position thereof relatively to the box or casing and adjacent mechanism or devices operated thereon. While the scoop has free movement in the box or casing 60, it is confined close enough by the latter to prevent interposition of the vended articles, materials, or substances between the same and said box or casing and support 2, and the upper part thereof serves as the lower end of an apportioning or measuring compartment 96,

having an automatically-operating bottom 97, swung on a rod or bar 98, supported by the box or casing at a necessary or preferred elevation above the normal resting position of the scoop. This bottom 97 consists of a plate forwardly curved, principally at its free end, and having sufficient weight to readily assume a depending position when all resistances are removed, and across the rear upper part of the scoop a rod 99 extends in rear of said bottom and has an adjusting-screw 100 seated therein, which can be easily reached through the opening 67 in the rear side of the box or casing and adjusted to regulate the elevation thereof and the consequent variation in the apportionment of the articles or materials to be vended. When the scoop descends far enough, the rod 99 and its screw 100 are depressed below and entirely free of the said bottom 97, and the latter will stand freely in depending position with the forwardly-curved free end projected over the path of movement of the said rod 99 and its screw and closes the said opening 67. Therefore when the scoop comes up or rises the forwardly-extending end of said screw strikes the rear surface of said bottom and gradually riding thereunder presses the latter upwardly into normal resting position. In this latter position said bottom shuts off the lower part of the scoop and is so held until the mechanism is regularly started to make a delivery.

The measuring-compartment 96 complete comprises in its organization the bottom 97 and upper part of the scoop, as stated, and also the surrounding part of the box or casing 60 above the same, as well as the adjacent part of the support 2, confined between the opposite parts of the box or casing by its application. The upper limit of said compartment is formed by an automatically-operating cut-off consisting in the present instance of gravitating gates 101, longitudinally disposed from front to rear and swung downwardly with oppositely-rotatable rods 102, which project to the rear through the upper part of the side 66 of the box or casing 60 and close to the bearings 63. On the rear ends of the rods 102 cam projections 103 are removable and adjustably secured and serve as counterpoises for the gates, but are particularly adapted to be engaged by a transversely-extending movable elevator 104, consisting in the present instance of a curved plate having rearwardly-extending arms 105 continuous with or attached to sleeves 106, provided with slots 107. The sleeves 106 are mounted on a rock-shaft 108 in the upper part of the bearings 63, and from said shaft headed studs 109 project and pass through the slots 107 to allow the sleeve 106 to have an independent limited forward rotation, but obstruct any rearward movement whatever. A spring 110 is coiled around the shaft 108 in opposite directions outwardly. The ends are made fast to said studs 109 and the center part between the coils drawn forwardly

and attached to the under central portion of the elevator 104. This independent movement for the elevator, through its connections, as set forth, allows the gates 101 to have yielding movement after they are temporarily locked closed and prevents jamming of a bulky article or material vended and obviates springing or bending of the parts and at the same time insures a practicable cut-off of a very sensitive nature and self-adjustable to compensate for varying resistance at times to its entire closure, yet by its automatic adaptation preventing dropping or falling of the vended article or material after an apportionment has been made and during the operation of delivery of the same. On the end of the shaft 108 nearest the starting mechanism a rearwardly-extending crank-arm 111 is firmly secured and has a spring 112 attached to its hub and the upper part of the support 2, which acts normally to hold the cut-off open. To the crank-arm 111 the upper end of a connecting-bar 113 is movably secured and extends down to the arm 114 of a bell-crank lever 115, swingingly secured on a hanger 116, held by the plate 8 of the starting mechanism. The arm 114 stands vertically and bears against a stop 117 on the plate 8 when the cut-off of the apportioning-chamber is open and by reason of the tension of the spring 112 transmitted through the intermediate devices. The outer arm 118 of the bell-crank lever 115 is horizontally disposed when arm 114 is vertical and serves as a locking projection for a gravitating dog 119, also pivotally attached to the hanger 116 at a lower level and outwardly or in advance of the said bell-crank. The pivot of said dog 119 is at the rear, and the greater part of the weight thereof is disposed at the front, and to prevent the dog from having a rearward throw beyond a predetermined limit a stop 120 is relatively situated near the upper rear edge thereof. In the top edge of said dog, at the front, a spring-actuated catch 121 is mounted and has a nose extending beyond the said edge and rear projecting over the upper edge to limit its movement.

An extension 122 projects forwardly and downwardly from the link 75, and thereto is attached the upper end of an adjustable trip 123, depending down through a guide 124 on the hanger 116 and having a shoulder or analogous device 125 at its lower portion. This trip is made adjustable in its structure to regulate its stroke and govern the time of operation of the parts which it actuates, and the shoulder or other device 125 coacts with the nose of the catch 121 on dog 119.

As shown in the main figures of the drawings, two rods 126 extend rearwardly from the lower end of the rear side 66 of the box or casing 60 in parallel planes any desired distance 130 and are equally spaced apart from each other. These rods are preferably removable in their attachment and have inclined knife-edge cutters 127 at their upper sides at the points

where they are applied to the box or casing. The rear ends of the rods are reduced and intended to pass through openings in bags 128, which are strung thereon in quantities and 5 regularly fed forward toward the box or casing by a follower 129, having openings therein to receive said rods and depending in the main below the latter. This follower presses equally against the full length of the bags 10 and is automatically moved by a weight 130, having a suspending-cord or analogous device attached to the upper rear part of the box or casing 60 and engaging a grooved pulley or roller 131 on the rear upper part of the 15 follower. The mouths of the bags are arranged to the front and are fed up in such relative position as to have the lip 82 of the scoop 78 enter and open the same, and at a proper time an individual separation of the 20 bags from the rods takes place. As each bag is separated from the rods the succeeding ones are proportionately moved forward and until the foremost one occupies a position to be operated on similarly to the preceding removed 25 one. Thus it will be seen that the bags are individually fed into place and each completely independent of its successors. While bags have been set forth to illustrate a practical operation, boxes or analogous devices 30 could also be used and fed in like manner.

An auxiliary attachment is mounted on the side of the box or casing nearest the starting mechanism for similarly opening the mouth of the bag to a limited extent to insure the 35 entrance thereof of the lip 82 of scoop 78. This attachment includes an oscillatable arm 132, swiveled intermediate its length just about on a line with the top of the slot 64, but in rear of the latter. The forward end 40 of said arm 132 is reduced and adapted to extend above and be operated by the adjacent trunnion 77, and has a spring 133 secured thereto and also to the lower part of the box or casing 60. This spring exerts a down- 45 ward tension on the end of the arm with which it connects and tends to pull up the rear end of said arm. To said rear end of the arm the upper end of a slide 134 is movably attached and has a slot 135 in the body there- 50 of for movement over a headed guide 136, fastened in the box or casing 60, and to the lower termination of the said slide a finger 137 is connected and has a limited movement under the resistance of a spring 138 and the relative 55 position of a shoulder 139 and a stop 140 on the connected parts. This finger extends rearwardly and has a reduced termination to easily enter and gradually open the mouth 60 of the bag to a certain degree from one side, the yielding attachment of said finger allowing it to conform to and overcome any minor obstruction in the initial operation and prevent tearing the material of which the bags are formed. To hold the front end of the 65 oscillatable arm 132 elevated and the slide 134 and finger 137 depressed, a locking-latch 140^a is located on the side of the box or cas-

ing 60 near the said parts and has angular projections or shoulders 140^b formed on its upper end to adapt it to ride and take hold 75 under the said front end of arm 132 by the pressure of a spring 140^c, bearing thereagainst above the pivotal or swivel point thereof. The lower end 140^d of said latch is normally disposed by the operation of the 80 said spring 140^c across the lower portion of the slot 65 on that side of the box or casing, and is released and the whole attachment afterward reset for a purpose in a manner, subsequently explained.

As a substitute for the bag feeding and guiding devices heretofore described the form of feeder shown by Figs. 19 and 20 can be employed and supported by suitable means properly positioned within the cabinet or enclosure 1. This modified form of device consists of a bottom plate 141, having at the rear upwardly-extending flaring sides 142, and from which guide-flanges 143 extend a greater part of the length of the said plate 141 and 85 toward the front end, which is open. To the rear edges of the sides 142 a bearing-plate or analogous support 144 is fastened, and from the same guide-tubes 145, 146, and 147 project forwardly and provide seats for guiding 90 plunger-rods 148, 149, and 150, having movement therein. These plunger-rods are of considerable length and are attached to or connected to the rear of a follower or pressure-head 151, which movably fits between 95 the sides and is automatically propelled forward by a spring 152, surrounding the tube 145 between the said follower and bearing-plate or support 144. By the use of the upper and lower guide-rods 149 and 150 the 100 follower is moved regularly and the pressure more nearly equalized thereby against the bags. As the parts are shown arranged they are adapted for use with bags having the full dimensional capacity of the attachment 105 and the spring 152 is at the center; but when smaller bags are used the spring may be changed in position and brought down on the tube 147, or if bags of considerably-larger proportions be employed the spring can be 110 mounted on the upper tube 146. These are obvious changes, and in some instances a greater tension might be desired than can be attained by the use of a single spring, and in this event two or all of the tubes 115 120 may be supplied with springs. At the front of this attachment yielding retaining-fingers 153 are secured to the flanges 143 and extend inwardly a short distance across the open front end above the bottom plate 141 125 and serve to prevent the bag as filled from slipping out of place too soon. An empty bag cannot be practicably forced past these fingers; but as it is filled the bulk increases 130 at the bottom and forces the said fingers 135 out far enough to permit the filled bag to readily pass. After the filled bag has passed out the fingers immediately resume the position shown to hold the succeeding

unfilled bag and ready for a successive similar operation. As shown by Fig. 19, angle-arms 154 can be used to attach the device at the rear end, and shouldered supports 155 to engage adjacent rests can be employed at the front. These features of support are unimportant, however, and can be changed at will within the suggestive purview of mechanical skill. Also at various points cross ties or braces 156 are applied to counteract spreading that might arise from the lateral pressure exerted by the bulk of the bags. When the bags are stacked or placed in this device, the follower 151 is shoved back its full limit between the sides and completely loaded from the front face of said follower to the spring retaining-fingers 153, the bottoms of the bags resting on the bottom plate 141 and movably confined by the flanges 143. In the drawings the follower is shown at a point between its extreme movements; but it will be understood that it pushes forward full length of the attachment to completely feed the bags.

On the inner lower portion of the face plate 25 or support 2 and relatively to the mechanism above a curved guide-plate 157 is secured directly behind an opening 158 of suitable dimension in the said plate or support at this point. The guide-plate 157 extends upward, 30 and on opposite sides thereof angular or analogous side closures 159 are stationarily applied and attached thereto, one of which extends up to the arm 37. On the closure adjacent the starting mechanism a vertical guard 160 is fixed and forms one side of a guide for 35 the delivery of the bagged or inclosed vended article or material. Pivot-supports 161 extend downwardly and rearwardly from the front lower portions of the closure 159, and thereto are movably attached the front ends 40 of arms 162 of a convex or equivalent cover 163. The grooved roller 57, carried by the lower arm 55, heretofore referred to in connection with the starting mechanism, is adapted 45 to bear on the upper edge of one of the arms 162, and projecting forwardly and upwardly from the arm is a pivoted catch 164, having a lateral projection 165 on the free end, and to the same arm a rear extension 50 166 is secured, to which the lower end of a retractile spring 167 is fastened and also to a lateral projection 168 on the box or casing 60. The front of the opening 158 is covered by a hood 169, open at the bottom and provided with a front aperture 170 and an upper glass-covered sight-opening 171, and covered by said hood is a delivery-gate 172, movably attached to the top wall of the said opening 158. To the right-hand side of the delivery-gate 65 a rigid latch 173 projects, having an angular projection 174 on its free end and reverse to and adapted to bear on the angular projection 165 on the adjacent free end of the catch 164. The latch 173 is held in proper position and in operative relation to the free end of the catch 164 by an inwardly-directed retention-pin or similar device 175, applied to

a side or wall of the guide, and over this mechanism is mounted a shield-plate 176 and secured in place on contiguous parts, being contained above the level of arm 37 in the form of a guard 177, which is slotted and has a greater rearward extent than the opposite guard 160. The cover 163 normally stands closed, owing to the retractile tension exerted thereon by the spring 167, and the rigid catch 164 is consequently lowered. When this cover is thrown back at the time the bagged or other inclosed vended article or material is delivered, it will be necessary to hold the same open for a time, and when in such open position the rigid catch 164 is brought up under the latch 173, which is always held in engaging position by the gravitation of the delivery-gate 172, carrying the same, and forced upward against the retention-pin 175. To provide an automatic lock for holding the cover closed when the machine is inert, a dog 178 is swung off the rear part of the closure 159, near the starting mechanism, and has a rear weighted end 90 179 and a front vertical releasing-finger 180, adapted to be engaged by the inner-projecting end of the pin or bolt 47, on which the dog 45 is mounted, and as said pin is drawn forwardly the dog 178 is released from the rear 95 of the cover. It will be understood that the mechanism just described is intended for preventing nefarious tampering with the internal device or frustrate an attempt to reach the article or materials for vendition from the exterior, and as a further safeguard for this purpose a toothed plate 181 is located at the top of the opening 158 and has a downward angle. As a substitute for these devices, however, the attachment shown by Fig. 18 may 100 be employed, and thereby dispense with considerable mechanism. This device consists of a tortuous-curved throat 182, communicating at its lower end with the hood 169 through the opening 158, and so shaped that the insertion of the hand of a person or wire or other device held thereby to any harmful distance will be prevented. The guards 160 and 177 may be used with advantage in connection with the throat 182, and in either event 105 posts 183 rise vertically adjacent to said guards and have fitted to the upper portions thereof inwardly-extending guiding-pins 184, one projecting through the slot of guard 177 and operates to prevent the bag or inclosure 110 and its contents in descending from toppling over and insure a deposit of the same into the delivery device below with the open end upward. This will avoid spilling of the said contents and present the bottom of the bag 115 or inclosure to the purchaser for withdrawal, and the convenience of such presentation is evident. Below the lower end of the hood 169 on the cabinet or inclosure 1 a receiver 185 is fastened, and into this the bag or inclosure 120 containing the vended article or material is intended to drop and also any of the latter that may become loose either accidentally above or during the fall from said hood. 125 130

Thus the purchaser will be given full quantity in accordance with the measurement of the apportioning-compartment.

The general operation of the foregoing structural features of the vending mechanism is as follows: The starting mechanism having the coin regularly positioned therein, the purchaser draws out the pull-bar 12 and throws the starting-lever 38 forwardly against the tension of the weight 43, as heretofore referred to. As said lever moves forward the actuating-dog 45 is likewise moved over the cam 50 and until the lug 46 drops ahead of the vertical edge 52 of said cam, and at this time the lever will have reached its full forward swing. Simultaneously with the forward drag of the dog 45 the projecting pin or bolt 47 will have unlocked the rear-weighted end 179 of the dog 178 from the rear edge of the cover 163 by engagement with the finger 180 and just immediately previous to the application of the downward-bearing pressure of the roller 57, carried by the lower arm 55 on the upper edge of the nearest arm 162, and throw the said cover open against the tension of the spring 167. As the cover opens, the fixed catch 164 thereon moves down correspondingly and becomes engaged by the end of the latch 173 on the delivery-gate 172 under the pin 175, thus holding the cover locked open and the gate closed with sufficient resistance to overcome the weight of the bagged or inclosed vended article, but easily opened, as will shortly appear, by the purchaser. Also as the pull-bar 12 moves forward the wiper 22 strikes the upper arm 114 of the bell-crank lever 115, throws it forward, and draws down the connecting-bar 113. Through this bar 113 and the rock-shaft 108, together with the intermediate mechanism heretofore set forth, the gates 101 are elevated and close or practically shut off the vended article or material fed into the apportioning-compartment from above and separate the same from similar articles or materials already resting in said compartment and now below said gates. At this time also the other arm 118 of the bell-crank lever descends in an arc and hits, tilts, and passes the rear end of the dog 119 and locks the latter against movement for a time. This preliminary setting takes place in regular sequence and at proper times and is entirely complete when the coin is relieved from the bar 12, and at this interval the purchaser will be made aware of a release of resistance to his pull and will naturally let go and the said bar will be automatically returned to normal position by the springs 27. Whether the bar is released or not by the purchaser will have no effect on the mechanism now about to move, as all control of the latter has now been lost and until another proper coin has been regularly inserted. Therefore the weight 43 now comes into play under the government of the cushion 40, and starting-lever 38 is now drawn rearward and the lug 46 of dog 45 forces the cam 50 over toward the rear, ro-

tates the shaft 36, and draws the crank-arms 53 and 54 downward. The said movement of these crank-arms pulls down the connecting-bars 73 and 74, attached to the crank-arms 69 and 72 on the rock-shaft 68, moves the latter, and raises the counterpoise-weight 71, and by means of the links 75 and 76, extending from the latter crank-arms and to the trunnions 77, the scoop 78 is gradually lowered with its contents. At the same time the trip 123, attached to extension 122 of the link 75, also correspondingly moves downward, and the shoulder 125 passes the catch 121 on the now locked dog 119. The scoop 78 continues to move down in a straight plane through the box or casing 60, being so guided by the studs 92 engaging the rear lower slots 88 and the trunnions 86 on the rod or other device 84 moving in the slots 65 in the sides of said box or casing. The lip 82, by its extension and angle in its downward movement, enters the mouth of the adjacent foremost bag, which is held open sufficiently for the purpose by the finger 137 on the slide 134 of the auxiliary opening attachment, and the bottom 97 of the measuring-compartment is also at the same time gradually depressed and by said operation allows the apportioned contents to feed into the lower part of the scoop, and the latter continues in its lowering movement until it has reached its full direct vertical descent, when the said bottom 97 will be completely opened and the articles or material vended will rest on the lower part of said scoop and be confined between the same and the surrounding part of the box or casing 60. At this time the studs 92 will be leaving the slots 88, and trunnion 86, near the starting mechanism, will have struck the lower end 140^a of the latch 140^a and thrown the upper end outward from under the front end of the oscillatable arm 132, permitting the spring 133 to pull down on said arm and elevate the slide 134, thereby raising and moving the finger 137 out of and away from the bag to be filled. Both trunnions 86 will now be bearing against the lower terminations of the slots 65 and serve as the axes for the further movement of the scoop. The trunnions 77 will not have quite traversed the slots 64 and their depression continues, and the resistance now set up by the trunnions 86 will cause the scoop to start to swing over toward the front, thus distending the mouth of the bag into which the lip 82 has been moving, and allow the articles or material to be vended and which has been resting in the scoop to gradually and fully pass into the bag. The bag as filled is at the same time drawn away from the feeding attachment therefor and if the rods 126 are used pulled off the latter and separated by the cutters 127. If the bag-feeding attachment shown in Figs. 19 and 20 be used, the bag will likewise be drawn out therefrom between the spring-fingers 153, as previously set forth. The filled bag as drawn clear of its feeding device falls or

gravitates and rests on the curved guide-plate 157 between the one side closure 159 and the shield-plate 176, being held upright by the pins 184. At this time the scoop will have 5 swung over, so that the plate 80 thereof is vertically disposed against the inner side of the glass panel 62 and will be entirely open, and portions or particles of the vended articles or materials that may have by any possibility 10 lodged above will be permitted to fall into the final-delivery mechanism below and move with the filled bag or other device toward and rest against the delivery-gate 172. The purchaser has had full view of this operation 15 through the panel 62, and his attention is also invited to observe such by a suitable inscription on the exposed side of the plate 80 of the scoop and by intuition or visible instruction inserts his hand up through the 20 open bottom of the hood 169. Meeting with the resistance or obstruction to obtaining the vended articles offered by the still-locked delivery-gate 172 he naturally attempts to remove the same and pulls the lower end of said 25 gate outwardly, thus releasing the latch 173 from the catch 164 of the cover 163, the bagged or inclosed article or material passes out, the said cover moves forward by action of the spring 167, and the weighted end 179 of the dog 30 178 drops behind the rear edge of the cover and locks the latter closed, and it remains firmly in this condition until regularly opened as before. If the throat 182 is used instead 35 of the delivery mechanism just set forth, the bagged or inclosed article or material will fall directly thereinto and pass outwardly therefrom without manipulation of any sort by the purchaser. Just about the time the filled bag or other device falls free into the final delivery device or devices the lug 46 on the actuating-dog 45 will have lost its engagement 40 with and cleared the edge 52 of the cam 50, because the rear part of said dog has been riding over the contact-head 48 and gradually 45 raised thereby. The counterpoise-weight 71, which has the function to restore the vending mechanism to normal set position, begins to descend as soon as the dog 45 is relieved from the cam 50, being heavy enough to overcome 50 the mechanical resistance and weight of the connected parts it controls. Thus the rock-shaft 68 is moved in reverse direction and the crank-arms 69 and 72 thereon are raised, pulling upward on the links 75 and 55 76, and through the trunnions 77 elevate the scoop 78. The front studs 91 will now be in engagement with the slots 90 of the scoop, and the front plate 80 will be caused to ascend in a vertical plane until the said studs 60 leave the slots 90, and at this time the trunnions 86 on the ends of rods 84 will have reached the upper ends of slots 65, the scoop 65 swung toward the rear, so that the lip 82 closes snugly against the rear deflected bot- tom portion 61 of the box or casing 60, and continues to move upwardly until the trunnions 77 strike the upper walls of the slots 64,

in which they travel. The trip 123 was also drawn up at the same time the immediate foregoing operation was proceeding, and the 70 shoulder 125 thereof, caught under the catch 121 on the dog 119, tilted the latter rearward and released the bell-crank lever 115, which allowed the rock-shaft 108 to be moved forward by the spring 110, simultaneously pull 75 up the connecting-bar 113, released the pressure of the elevator 104 from the cam projections 103 on rods 102, and thereby permitted the gates 101 to fall down and open the upper part of the apportioning or measuring 80 compartment 96 to the feed from above just as the scoop has completed its full upward movement. During the rise of the scoop the dumping-bottom 97 will have been gradually drawn up by the rod 98 and the compartment 85 96 will be again completely arranged for a subsequent similar operation. As soon as the trunnions 86 begin to move upward the one nearest the starting mechanism releases the latch 140^a and the spring tension thereon 90 causes the upper end to be thrown rearward and rests against the depressed front end of the oscillatable arm 132 and remains in such position until the nearer trunnion 77 strikes and pushes up the said latter arm against the 95 tension of the spring 133, when the upper end of latch 140^a will automatically slip under the front end thereof and at once force the slide 134 downwardly and rearwardly and direct the finger 137 thereon into the side of the 100 mouth of the next empty bag which was pressed into place immediately after its filled predecessor was released. All the vending mechanism proper will now stand ready for further operation and the vended article or 105 material will have been deposited by gravitation in the compartment 96 and the starting-lever 38 will be fully to the rear and the dog 45 have its lug 46 resting on the upper curved edge 51 of the cam 50. 110

When either form of bag-feeding attachment is emptied, the follower thereof will be forced to the front in full view through the panel 62 and have applied thereto a notice to the effect that the machine is empty and not 115 to insert the coin. This will prevent a useless waste of the coin and obviate aggravation or dissatisfaction on the part of an intending purchaser. As a further notice in this direction the upper part of the cabinet 120 or inclosure will be provided with a frame or holder 186, in which a stop or other instructive card may be placed and easily viewed from the front. A necessary and advantageous accessory to this form of machine, and 125 particularly the vending mechanism proper, is a hopper 187, which has a contracted bottom 188 resting directly on the upper surrounding edge of the box or casing 60. Surrounding this compartment is a hot-air chamber 189, 130 having a hot-air flue 190 connected thereto and extending down to a heater 191. Within the heater-body is a coil 192, attached at its lower portion to a water tank or reservoir 193

at one side and the supply of water made regulable by a valve 194, and from the upper part of said coil a steam-pipe 195 passes up through the flue 190 to a whistle or analogous device 196. This heating attachment is intended to be used when vending peanuts or other articles or materials required to be heated, and the steam-whistle directs attention of passers-by to the machine. Thus when peanuts are vended the machine will be equipped with all the appurtenances ordinarily used by the manual peanut-vender. These heating and signal attachments, however, need not be used when heat is not required, and the machine can be used independently thereof. Thus the same machine is arranged for all uses or modes of vending without requiring a structural change or rearrangement.

The number of bags or other devices employed may have unitedly a greater capacity than that of the hopper 187, and to avoid confusion and loss to an intending purchaser automatic means are employed for preventing the insertion of a coin when the article to be vended has become exhausted. It therefore becomes necessary to provide against such contingency, and consequently the interposition of positively-resisting means is imperative when the machine is in the condition stated. This obstructive mechanism comprises a plate 197, placed adjacent the contracted bottom 188 of the hopper 187 on the side nearest the starting mechanism. This plate is secured to the upper end of one arm of a lever 198, which is suitably fulcrumed, and to the free end of another arm thereof is attached the upper end of a locking-rod 199, movable vertically through guides 200, located at a suitable elevation on the inner side of the support 2. The lower end of rod 199 is adapted to lie vertically across the coin-entrance slot and also to engage a part of the coin mechanism hereinafter described. Between the guides 200 the rod 199 has a spring 201 surrounding and connected to the same, and when the hopper 187 is filled or so long as the contents remain therein the weight of the same on the plate 197 will cause the latter to be pressed close to the adjacent side of the contracted bottom of said hopper and through the lever 198 hold the rod 199 elevated against the resistance of the said spring 201. These parts are so sensitive that a small quantity of the contents of said hopper will act on the plate 197, and the latter being located low in the bottom of the hopper, as shown, will not move away from the adjacent side until the hopper has been entirely relieved of its contents. As soon, however, as pressure is relieved from the plate 197 it is moved away from the part of the hopper against which it has been pressed by the spring 201, and the rod 199 descends across and in rear of the coin-entrance slot.

As a further part of the vending mechanism a variation in the form of part of the

scoop 78 is shown by Fig. 17^a and consists of a reduced pliable or yielding lip 202, adapted to enter the mouth of a bag and conform to irregularities or open a sticking mouth by bending and easily forcing an entrance. Under certain conditions the bag material around the mouths may be pressed close into the body thereof, particularly when said material is thin, and so remain by frictional pressure or otherwise. This yielding reduced lip will act to readily separate the temporarily-adhering parts and insure a passage of the vended articles or material thereinto. A further change is readily suggested in the event that it is desired to close the bag-mouth after filling. This is accomplished by lowering the swivel or pivot bearings of the cover 163 so as to bring the front edge thereof against the upstanding bag-closure when swinging forward. No material change is necessary in making this alteration and is merely a matter of degree. It is intended also that the bags or other inclosing devices in which the vended materials or articles are placed for delivery have advertising matter imprinted thereon and advertising samples of various manufactured goods placed therein before assemblage on the feeding devices therefor. This will minimize the expense of the machine and make the profits entirely clear of and, in fact, in many instances in excess of the expenditure for articles or material to be vended thereby, as contracts can be entered into covering an income from delivery of such bags and samples and regulable proportionately to the number vended.

Coin mechanism.—This mechanism includes many advantageous features and comprises an entrance-slot 203, inclined slightly from the horizontal and formed similarly in an escutcheon 204, fixed to the exterior of the support 2 and also in the latter. The slot 203 coincides with the outer upper end of a slotway 205, having sufficient declination to cause a rapid movement of the proper coin therethrough and also provided with incidental structural features and attachments for preventing the fraudulent operation of the same and the loss of certain coin. At the outer end of the slotway is a flange 206, having an inclined slot 207 in alinement with the slot 203, and immediately following the flange are opposite rails 208 and 209, the rail 208 being higher than rail 209, so as to cant the coin that properly passes thereover. Between the rails is an opening 210, which is less in cross extent than the diameter of a coin required to operate the machine and having a regular form. If a mutilated coin of the required denomination be inserted, varying in thickness by reason of being punched or plugged and in diameter by edge wear, indentation, or flattening, a resistance will be first offered to the insertion of such a coin by the slot 203, as the latter is reduced in width and length to a minimum relatively to a legitimate coin and a punched or plugged coin is increased in thickness or

diameter and greater than the dimensions of said slot, and efforts to enter the same will be ineffectual. If the mutilated coin be less in dimension than the slot and pass through 5 the latter, owing to some other peculiarity of the defacement or disfigurement, it will fall through the opening 210 and be directed by a chute 211 to an outlet-slot 212 and into an exterior cup 213, located under the latter slot. 10 The chute 211 has opposite inclosing sides 214 and a rear forwardly-inclined wall 215, having a central slot 216 therein. The upper front part of said wall 215 is thickened to project slightly and formed with an inclined 15 face 217 to throw the coin over toward the bottom of the chute and prevent contact with a part more fully hereinafter set forth. By this means also coins in perfect condition of a different denomination that may be inserted 20 either ignorantly, accidentally, or with intention to operate by use of same and having a smaller diameter than the designated operating-coin will also drop through the opening 210 and fall into chute 211 and through 25 the outlet 212 into the cup 213, and thus exteriorly returned. To prevent irregular coin or other devices from being impulsively propelled or driven into the slotway beyond the obstructing or detecting devices for the same, 30 a movable drop 218 gravitatingly depends into the slotway and adjacently in rear of the slot 203, so that an obstruction or stop is instituted to cause such coin or device to be directed to the opening 210 or influenced by the mechanism 35 farther along in said slotway. This drop also similarly acts on legitimate coin of the proper denomination when inserted in a like manner and prevents loss of same or improper guidance thereof. In this drop an opening 40 219 is formed, through which the lower end of the rod 199, heretofore referred to, passes in its downward movement and locks said drop closed as well as obstructing the passage of coin through the slot 203. Immediately succeeding 45 the rails 208 and 209 a plate 220 is situated in the slotway and is formed with a central longitudinal slot 221. The upper surface 222 of this plate is roughened, and lying partially thereover at an angle of inclination 50 is a movable shield 223, carried by a cross-pin 224 and having a finger 225 at one side to bear on a part of the slotway and limit the upward throw of said shield, and also has an under projection 226 to fall into washers or 55 other devices having openings therein to stop them. Directly below the plate 220 and fastened to the under side of said slotway is a magnet 227, and on the poles of the latter said plate directly rests and becomes magnetized 60 therefrom. The roughened surface of plate 220 causes an adhesion of lead slugs or other soft-metal devices, and the magnetism of the plate stops all devices that can be magnetically affected. Movable between the poles 65 of the magnet and up through the slot 221 of the plate 220 is an expeller 228, pivoted at its rear portion and having a widened front end

in a vertical direction normally depending below the under side of the slotway. To the under part of the said widened front end of the 70 expeller an arm 229 extends at a rearward incline and has a cross-pin 230 in the free end thereof. Projecting forwardly from said arm is a finger 231, which moves or plays in the slot 216 of the chute 211. Pivotedly secured 75 to the face or support 2, just below the chute 211, is a trigger 232, having an upper rear contacting nose 233 and a top recess 234, formed in part by the nose, and in which the arm 229 and cross-pin 230 of the expeller 228 80 loosely rest. This trigger is sufficiently heavy to always assume its normal position when not engaged by the actuating mechanism therefor and at its lower portion has a depending lip 235 in the path of movement of 85 and adapted to be struck by a vertically-disposed projection 236 on the upper front portion of the pull-bar 12 of the starting mechanism. The upper edge of the expeller 228 is formed with a recess 236^a and provides a rear 90 heel or contacting projection 236^b, having its upper edge normally flush with the adjacent roughened surface 222 of the plate 220, so that regular coins may pass thereover without obstruction. When slugs, washers, tokens, or 95 other improper devices are inserted, they will be held on plate 220 in advance of the heel or contacting projection 236^b and under the movable shield 223 and removed regularly, as will be presently set forth. 100

Below the location of the plate 220 a guide 237 is secured on the upper part of the slotway and disposed at an angle transversely of said slotway. The outer top edge of the slotway is cut away in the rear of said guide, and the latter is preferably formed of bendable sheet metal, though it may be cast or cut, if desired. This guide has a trough or receptacle 238 at the outer side, and at the rear-most edge a flange 239 stands up and is continued through the entire transverse extent of the trough, and that part of the guide standing over the slotway covers the latter and also forms an inclined slide to direct devices thrown or placed thereon to the trough or receptacle. When a slug, token, washer, or 110 analogous device is inserted for the purpose of operating the machine, it is retained on the plate 220 over the expeller 228 and in advance of the heel or projection 236^b. After insertion of such device an attempt will be made to pull out the bar 12, and this will move for a limited distance and until the locking-yoke interposes its resistance, as it has not been properly released. The outward movement 115 of the bar is sufficient, however, to permit the projection 236 thereon to pass the lip 235, which moves to allow such passage, and the resistance to a further withdrawal will cause a let-go action, and the springs 27 will suddenly retract said bar. This rearward movement of the bar will bring the projection 236 120 with force against the lip 235, which is immovable in that direction, and the trigger 232 125

- is quickly thrown up and the expeller 228 likewise raised thereby and elevate the slug, token, washer, or other device thereon. As said expeller is swiveled or pivoted at its rear 5 end, it will assume a rearward and downward incline when raised, and the device being expelled thereby will be caused to rest against the heel or contacting projection 236^b and be thrown over on the guide 237 and slide into the trough or receptacle 238. If the slug, token, washer, or other device deposited on the guide, as stated, slide the full length of the same, it cannot escape, as the flange 239 will prevent further movement in a downward direction, and the function of the shield 223 is to obviate a too forcible throw of such device by the expeller and always insure a deposit thereof on the guide and held in convenient position for after removal by an authorized person having access to the interior 10 of the cabinet or inclosure 1. The limitation of the upward movement of the shield 223 is so arranged as to dispose it at a self operating or gravitating angle and a return thereof to a 15 normal position.
- Children and idle persons will at times mischievously insert bits or pieces of orange or lemon peel and paper in the coin-entrance slots of vending-machines and also with a 20 purpose to operate thereby, and unless removed said bits or pieces choke the slotway or coin-passage and seriously interfere with the proper manipulation of the mechanism. This contingency has also been duly considered in the present instance, and to guard 25 against the same the finger 231 on the expeller 228 is utilized. This finger projects through the slot 216 in the rear wall 215 of the chute 211 and freely and quickly moves 30 up through the opening 210 between the rails 208 and 209 every time the expeller is actuated, as before set forth. The said bits or pieces are thus forced out of the slotway and cast off to one side.
- 35 The slotway under the guide 237 and immediately following the rear end of the plate 220 is open at the bottom and has opposite guides 240, and if by any manner of means a mutilated or undersized coin should slip 40 through above it will fall between the guides 240 and never reach an operating position in the starting mechanism. The lower under part of the slotway has a plate 241 secured thereto, with an angular extension 242 and a 45 downwardly-projecting bifurcate guard-lip 243 depending into the coin-receiver 15 and serves to direct the coin to the latter. On the extreme lower part of the slotway, above the plate 241, a small rock-shaft 244 is mounted and has an angularly-projecting end 245, which is held against the rear of the pin 21 on the outer side of the receiver 15. Centrally of said shaft 244 the upper end of a keeper 246 is movably fixed to turn or move 55 therewith and depends into the opening 18 between the lugs 17 of said receiver 15. On top of this lower part of the slotway a flat or

plate spring 247 is secured and covers said slotway from the rear limit of the guide 237 down to the rear end of same. At its lower termination 70 said spring 247 is projected beyond the slotway and is reduced, being formed at this point with depending arms 248, which loosely embrace the upper adjacent part of the keeper 246, and on the latter the part of 75 the plate between the arms has bearing and holds the said keeper with sufficient resistance to repel movement thereof by the weight of or forceful impact that may be given the coin by its fall. When the bar 12 is at rest, 80 the transverse opening 19 is located back of the rear end of the slotway a short distance. The coin is held at the rear end of the slotway in a vertical plane until the starting forward movement of the bar 12 brings the transverse opening 19 thereunder, and said coin then drops down and acts on the starting mechanism by a continued outward movement of the bar, as already explained. When the bar is at rest, the pin 21 bears against 85 the projecting end 245 of the shaft 244 and forces the keeper 246 back far enough to clear the rear end of the slotway and permit the coin to unobstructedly fall into the transverse opening 19 at the proper moment. If an 90 attempt is made to draw the bar 12 outward too quickly after the insertion of the coin and before the latter has been deposited in the opening 19, the keeper 246 will be instantly forced by spring 247 against the bifurcate 95 guard-lip 243 at the rear end of the slotway and close the latter as soon as the pin 21 is free of the angular projecting end 245 of the shaft 244 and hold the coin in said slotway. The locking-yoke 28 will prevent the bar from 100 going out beyond a certain limit, because there is no coin in place to actuate the starting mechanism, and the purchaser under these conditions meeting with a resistance will naturally release the bar and the springs 27 draw 105 the same automatically inward into normal position. This inward movement of the bar will force the keeper 246 away from the end of the slotway, and the coin which has been held back is now free to fall into the receiver 110 115 and ultimately become seated in the opening 19 by a subsequent pull and outward movement of the bar, and this time the mechanism will be set in motion and the purchaser will receive the vended article or material. 115 By this means a coin cannot become lost and a purchaser always receives a return value for his deposit.

Registering mechanism.—At the point where the sight-opening 59 is located in the 12 face-support 2 a small compartment is formed, in which a receiver 250 is fitted and has the front and a part of the top open, as at 251, and shown in detail by Fig. 16. The top has a guide-lip 252 standing up therefrom, and 13 within said open part a tilting plate 253 is situated and has its upper edge attached to a pintle 254, that projects through one side of the receiver. Radially extending from said

projecting part of the pintle is a stop or pin 255, which is fitted in the slot 256 of a disk 257, movable on said part of the pintle, and provided with a contacting nose-cam portion 258 and also has secured thereto one end of a loop or analogous spring 259, which in this instance is connected at its opposite end to said pintle. In the rear upper part of the receiver is a rock-shaft 260, having a retractile spring 261 secured thereto and to the top part of the plate 253 to assist in closing the latter and bring the cam 257 up to arrange its nose 258 in relative position to a contacting surface 262 at the front end of a lever 263, attached to an extended end of said shaft 260 and movable on the same side of the receiver as the said cam. This lever projects rearwardly under the rod 56, carried by the lower arm 55 of the starting mechanism, and thereon is a supporting-head 264, having a depending leg 265. From the receiver 250 a throat 266 extends downwardly to a coin-deposit box or receptacle 267, adapted to have a door with a lock, and on the top thereof is immovably placed a registering device 268 of any preferred form and provided with a contact-plate 269 on the upper end of a spring-controlled actuating-stem 270. The contact-plate 269 is operatively situated below the lower end of the leg 265, carried by the lever 263, and the latter after depression always returns by spring influence to a normal position and so that the contacting surface 262 will secure an engagement with the nose 258 of cam 257. As the said contacting surface lowers the adjacent part of the lever 263 presses itself past the cam, the latter moving by virtue of the slot 256 therein sufficiently for said purpose, and is then snapped or brought into regular position by the spring 259.

As a coin is being drawn forward by outward movement of bar 12 to actuate the starting mechanism the rod 56 of the latter is gradually drawn to and finally moves rearward against and over the upper edge of the lever 263 and presses the latter down and registers a deposit at the same time the coin will have reached and fallen through the chute 58 and on the tilting plate 253 and rested for a time, and as the said lever 263 is fully depressed said tilting plate will be released and allow the coin to enter the receiver 250 and pass down through the throat 266 into the box or receptacle 267. As the starting mechanism is set in motion the pressure of the rod 56 is relieved from the lever 263 and the latter and other parts coacting therewith will resume a normal position and be ready for a successive similar operation. The registering device 268 will also be supplied with any suitable locking device, and tampering with the same thus prevented. The means for unlocking said registering device and the box or receptacle 267 will be in the keeping only of authorized persons, and accurate registration may be thereby maintained. It will be observed that the registration of the

amount of deposited coin must always be equal to the number of bags or inclosures of vended articles or materials, and consequently will efficiently and reliably serve to designate the total number of vended bags or inclosures carrying advertising matter that may have been contracted for at a price proportionate to a certain number delivered. 70 By examining this registering mechanism the parties furnishing the bags or advertising matter under such conditions can become readily and positively informed as to the number or quantity vended and obviate disagreements or contentious disputes that might otherwise arise. 75

Display advertising mechanism.—In the upper part of the vending mechanism a front opening 271 is provided in the cabinet or 85 casing 1, and a display-compartment 272 is formed thereat by opposite side and top and bottom mirrors 273, setting up a multiple reflection that may be clearly discerned by pedestrians coming toward the machine from 90 opposite directions and also directly in front. In the rear of this display-compartment a rotatable skeleton drum 274 is mounted and simulates the play-cylinder of a squirrel-cage in its structure in that it has opposite heads 95 connected at regular intervals by longitudinal wires or rods. On each wire or rod is removably attached the inner edge of an advertising-card 275 by means of clips 276. These cards have the two sides thereof exposed by the rotation of the drum carrying them and are first brought up straight at the top of the display-compartment to show one side and then drop down gradually and show the opposite side. It is intended that printed 100 advertising matter be applied to one side of each card and pictorial matter to the other, and thus diversify the display. The advertising matter will also be made more effective and attractive by alternately arranging 105 cartoons among the cards embodying political and other topics of the day.

The axis 277 of the drum 274 is mounted in suitable bearings and has thereon at one side a gear 278, in mesh with another gear 279 of 115 suitable spring-motor mechanism 280, that can be wound at intervals and perpetuate the movement of the advertising matter. A suitable lighting device might also be placed in or relatively to the display-compartment, so that 120 the advertising matter can be seen at night.

The machine shown by Fig. 1 illustrates peanuts as the articles to be vended; but it is not limited to such articles, and other materials, as previously stated, can be equally well handled thereby. In fact, the vending mechanism set forth is a mechanical clerk, having an automatic mode of vendition and including auxiliaries and accessories which will naturally increase its value by protecting it against all known irregular practices and nefarious manipulations. 125

Having thus described the invention, what is claimed as new is—

1. In a vending-machine, vending mechanism, a movable member adapted to receive a coin, a shiftable part coacting with the movable member, and a lock adapted to be gradually opened by the shiftable part and release the movable member, substantially as set forth.
2. A coin-controlled vending-machine comprising a slotway having a keeper at its rear portion, starting mechanism having a slideable member with which said keeper coacts, and automatically-operating vending mechanism.
3. A coin-controlled vending-machine comprising starting mechanism adapted to receive an operating-coin and including a slideable member and a swinging part adapted to be shifted in one direction by an inserted coin and automatically returned to normal position thereafter, and vending mechanism set and started by opposite positions of the said swinging part.
4. A coin-controlled vending-machine comprising starting mechanism including an outwardly-movable member and a shiftable part coacting therewith, and adapted to be operated by the direct pressure of a regularly-inserted coin, a lock adapted to be gradually opened by the shiftable part and release the movable member, and vending mechanism conjunctively related to said starting mechanism and adapted to be set by the forward or outward movements of the said member or part and automatically operated by the return of said part.
5. A coin-controlled vending-machine comprising a starting mechanism having an outwardly-movable member adapted to be manually withdrawn and automatically returned to a normal position, the said member having a coin-opening to receive a regularly-inserted coin in vertical position, a shiftable part free of but in operative relation to the said member against which the coin is directly brought to bear, and vending mechanism adapted to be set by the outward movement of the shiftable part and actuated by the return of said part to its normal position.
6. Coin-controlled vending mechanism comprising coin-actuated starting mechanism including an outwardly-shiftable member adapted to be manually operated, and vending mechanism including a supply device, an apportioning-compartment, a cut-off between the supply device and apportioning-compartment, filling and delivery devices, the cut-off between the apportioning-compartment and supply device being closed by the outward movement of the shiftable member, and counterpoise mechanism actuated by the automatic return of said member which will again operate to open the cut-off after delivery has been made.
7. A coin-controlled vending-machine comprising a starting mechanism, and vending mechanism conjunctively related thereto, the said vending mechanism including in its organization a filling device adapted to open and enter the mouth of one of a series of inclosures and disengaging them separately after filling the same.
8. A coin-controlled vending-machine comprising starting mechanism, and vending mechanism conjunctively related thereto and including a movable filling device and an inclosure-feeding mechanism, said movable filling device having a part thereof adapted to enter the mouth of an inclosure, deposit the vended material or article and separately disengage the inclosure after filling the same.
9. A coin-controlled vending-machine comprising a starting mechanism, and a vending mechanism conjunctively related thereto and including an automatically-movable filling device having an actuating member set in motion thereby and inclosure-feeding devices adapted to be opened, filled and separately disengaged by the movement of said filling device.
10. A coin-controlled vending-machine comprising a starting mechanism, a vending mechanism conjunctively related thereto and including a movable filling device having an actuating member controllable thereby, a cut-off having a timed operation, a supply device and inclosure-feeding mechanism wherefrom the inclosures are separately fed to and disengaged by the filling device.
11. A coin-controlled machine comprising starting mechanism, vending mechanism conjunctively related thereto, and inclosure-feeding mechanism adapted to successively move the bags or inclosures in separate condition to the vending mechanism for the purpose of receiving the vended article or material which reacts on the inclosure-restraining means to effect an automatic release of the inclosures.
12. A coin-controlled vending-machine comprising starting mechanism including a member adapted to be manually drawn outwardly after the regular deposit of the prescribed coin and in its outward movement release a locking resistance and to be self-locked against a return movement previous to a full distention by the intermediation of the coin, and vending mechanism conjunctively related thereto.
13. A coin-controlled vending-machine comprising starting mechanism including an outwardly-movable member adapted to be manually operated and having an automatic lock adapted to be released when the prescribed coin has been regularly deposited in said member, a slotway having a keeper automatically movable thereon, whereby too-rapid withdrawal of the member is provided against prior to the deposition of the coin, and vending mechanism conjunctively related to said starting mechanism.
14. A coin-controlled vending-machine comprising starting mechanism including a forwardly-shiftable member under automatic return stress having projecting portions, and vending mechanism conjunctively related to

5 said starting mechanism and adapted to be first set in part by certain of the projecting portions of the said member in its forward movement and automatically actuated by certain other projecting portions of the said member in its rearward movement, substantially as and for the purpose specified.

15. A coin - controlled vending - machine comprising starting mechanism, and vending mechanism conjunctively related thereto and including apportioning, filling and delivery devices adapted to be first set in regular order, then actuated for successive operation and afterward reset in normal position by stress mechanism operating independently of any part of the starting mechanism.

16. A coin-controlled machine comprising starting mechanism including an outwardly movable member and a shiftable member free of and operatively related thereto and adapted to be released and actuated after a prescribed coin has been regularly deposited therein, a wiper, carried by the said shiftable member and movable with reference thereto, and vending mechanism conjunctively related to the said starting mechanism and first set by a part of the shiftable member during its outward movement and subsequently actuated by the aforesaid wiper.

30 17. A coin - controlled vending - machine comprising starting mechanism including a
slidable member adapted to be manually drawn outward, and a movable member forcibly shiftable in one direction and automatically movable in the other direction, and vending mechanism conjunctively related thereto and including a supply device having a coin-entrance-controlling member, an apportioning - compartment, a cut-off between the supply device and apportioning-compartment, a movable filling device, mechanism for separately feeding the bags or inclosures to the filling device, and means under stress for automatically afterward returning said parts
40 to a normal position, all of which are primarily set by the movement of part of the starting mechanism in one direction and actuated by the reverse movement of the same.

45

18. A coin - controlled vending - machine comprising starting mechanism, and vending mechanism conjunctively related thereto and to which articles, materials or substances are fed in bulk and automatically apportioned thereby in predetermined quantities, deposited in individual bags or other receptacles, separately fed into receptive position, and delivered to the purchaser in package, convenient carrying or inclosed form, said vending mechanism being primarily set by a movement of the starting mechanism in one direction and afterward actuated by a reverse movement of part of said starting mechanism.

50 comprising starting mechanism, and vending mechanism conjunctively related thereto and to which articles, materials or substances are fed in bulk and automatically apportioned thereby in predetermined quantities, deposited in individual bags or other receptacles, separately fed into receptive position, and delivered to the purchaser in package, convenient carrying or inclosed form, said vending mechanism being primarily set by a movement of the starting mechanism in one direction and afterward actuated by a reverse movement of part of said starting mechanism.

55 comprising starting mechanism, and vending mechanism conjunctively related thereto and to which articles, materials or substances are fed in bulk and automatically apportioned thereby in predetermined quantities, deposited in individual bags or other receptacles, separately fed into receptive position, and delivered to the purchaser in package, convenient carrying or inclosed form, said vending mechanism being primarily set by a movement of the starting mechanism in one direction and afterward actuated by a reverse movement of part of said starting mechanism.

60 comprising starting mechanism, and vending mechanism conjunctively related thereto and to which articles, materials or substances are fed in bulk and automatically apportioned thereby in predetermined quantities, deposited in individual bags or other receptacles, separately fed into receptive position, and delivered to the purchaser in package, convenient carrying or inclosed form, said vending mechanism being primarily set by a movement of the starting mechanism in one direction and afterward actuated by a reverse movement of part of said starting mechanism.

65 19. A coin - controlled vending - machine comprising in its organization starting mechanism, and vending mechanism conjunctively related thereto and including a movable filling device with a lower projection and mech-

anism for separately feeding bags or inclosures into receptive position and into the mouths of which the said projection of the filling device is adapted to enter, the said vending mechanism being primarily set and actuated by the starting mechanism.

20. A coin - controlled vending - machine comprising starting mechanism, and vending mechanism conjunctively related thereto and including a filling device having a regularly-descending vertical movement, a forward swing and subsequent vertical elevation, and a final reverse swing to thereby deposit its contents in a bag or receptacle, disconnect the latter and return to normal position. 75 80

21. A coin - controlled vending - machine comprising a starting mechanism, and a vending mechanism conjunctively related thereto including a filling device having a differential movement in opposite rear and forward directions, and an actuated bottom successively opened and closed by the movements of said filling device. 85

22. A coin - controlled vending - machine comprising starting mechanism, and vending mechanism including a supply device, and cut-off, filling and delivery devices, the cut-off being closed by the final movement of a part of the starting mechanism and previous to the actuation of the remaining vending mechanism and opened ultimately after the said latter mechanisms have operated and returned to normal position. 95 100

23. A coin - controlled vending - machine comprising starting mechanism, and vending mechanism conjunctively related thereto and including a filling device normally disposed at an angle and having a downward, forward, upward and rearward movement during successive operations thereof. 105

24. A coin-controlled vending-machine comprising starting mechanism, and automatically-operating vending mechanism intimately related thereto and including a filling device and a movable bottom adjustable relatively to the said filling device and operated by the latter.

25. A coin-controlled vending-machine comprising starting mechanism, and vending mechanism conjunctively related thereto and including a filling device, inclosure-feeding mechanism to place the inclosures in receptive position to be engaged by the said filling device, and an auxiliary attachment for initially opening the inclosure. 115 120

26. A coin - controlled vending - machine comprising a starting mechanism, and a vending mechanism intimately related thereto and including a supply cut-off and filling devices, the supply cut-off having a self-compensating adjustment. 125

27. A coin-controlled vending-machine comprising starting mechanism, vending mechanism intimately related to said starting mechanism, including a cut-off primarily closed by the initial operation of the starting mechanism and having a self-compensating

ing adjustment and afterward automatically opened by mechanism operating independently of that which closed it.

28. A coin - controlled vending - machine comprising starting mechanism, and vending mechanism intimately related thereto, the vending mechanism including in its organization a cut-off primarily closed by the initial operation of the starting mechanism and ultimately reopened by devices automatically movable independent of said starting mechanism.

29. A coin-controlled vending mechanism comprising starting mechanism, and vending mechanism intimately related thereto, the said vending mechanism including in its organization a filling-scoop having slots at different points in opposite sides, means for lowering and raising the said scoop, yielding device to engage the said slots and maintain a regularity of movement of the scoop in certain directions at predetermined intervals.

30. A coin - controlled vending - machine comprising starting mechanism, and vending mechanism intimately related thereto, the vending mechanism including in its organization a box or casing, a filling device normally disposed at an angle in said box or casing and having vertical movements and swings in opposite directions, and a feeding device for delivering bags or inclosures separately in receptive position to the said filling device.

31. A coin - controlled vending - machine comprising starting mechanism having contacting movable devices thereon, and vending mechanism intimately related to said starting mechanism and including a cut-off having connected devices located in the path of movement of a part of the movable devices on the starting mechanism whereby the said cut-off is closed on the outward movement of said starting mechanism previous to the actuation of the remaining portion of said vending mechanism.

32. A coin - controlled vending - machine comprising starting mechanism having contacting devices thereon, vending mechanism intimately related to the starting mechanism and including in its organization a cut-off with connected devices located in the path of movement of a part of the contacting projections of the starting mechanism and under resisting stress, a trip attached to and movable by said connecting devices, and a lock adapted to be released by the trip to open the cut-off after the remaining portions of the vending mechanism have returned to their normal positions.

33. A coin - controlled vending - machine comprising a starting mechanism, and a vending mechanism intimately related thereto and including a feed cut - off primarily locked closed by the movement in one direction of said starting mechanism and ultimately released by a return of certain of the remain-

ing parts of the vending devices to their normal positions.

34. A coin - controlled vending - machine comprising starting mechanism, and vending mechanism intimately related thereto and including in its organization, supply, cut-off, filling, bag or inclosure feeding and final-delivery devices, the said delivery device being primarily opened by the initial operation of the starting mechanism and adapted to be closed by the purchaser in obtaining the vended article or substance.

35. A coin - controlled vending - machine having a final-delivery mechanism primarily opened by the actuation of preceding devices including a coin-controlled starting mechanism and ultimately closed by passage of article delivered.

36. A coin - controlled vending - machine having a final-delivery mechanism comprising a swinging cover carrying a part of a lock and primarily opened by the initial operation of other devices, including a coin-controlled starting mechanism and a delivery-gate also carrying a part of the lock and adapted to be operated by the purchaser to release both parts of the lock and permit the cover to close automatically.

37. A coin - controlled vending - machine, and devices for actuating the same and including a coin-controlled starting mechanism bag or inclosure feeding device and inwardly-extending yielding devices 153 to hold the filled bag or inclosure in upright position 100 when it falls into the final-delivery device.

38. A coin - controlled vending - machine comprising starting mechanism, and vending mechanism intimately related thereto and including an inclosure-feeding device and an auxiliary attachment for engaging the mouths of the inclosures preliminarily to the entrance thereto of a part of the vending mechanism.

39. A coin - controlled vending - machine comprising a starting mechanism including a 110 slidable member having a slot therein and a coin-receiving opening, a starting-lever having a part normally situated in said slot and free of the slidable member and provided with fixed and movable offstanding operating 115 portions, and vending mechanism intimately related to said starting mechanism.

40. A coin - controlled vending - machine comprising starting mechanism including a 120 slidable member having a slot therein and a coin - receiving opening and projections, a starting-lever having fixed and movable off-standing operating portions, a lock automatically opened by the movement of the starting-lever, means for returning said slidable 125 member and starting-lever to their normal positions, and vending mechanism intimately related to said starting mechanism.

41. A coin - controlled vending - machine comprising starting mechanism including a 130 fixed and a slidable member the former having a slot therein and ratchet-bars disposed

on opposite sides thereof and the latter having a transverse coin-opening wherein a regularly-deposited coin is disposed in upright position, a starting-lever relatively extending into said slot of the fixed member but free of the slidable member, whereby a coin is brought into direct contact with the said lever and diametrically opposite parts caused to engage the ratchet-bars to prevent a dual or multiple vendition by the use of a single coin, and vending mechanism operatively related to the said starting mechanism.

42. A coin - controlled vending - machine comprising starting mechanism including a fixed and a slotted slidable member the former having ratchet-bars disposed therein, and the latter having a rear coin-opening wherein a regularly-deposited prescribed coin is vertically disposed and adapted to engage the ratchet-bars and lock the slidable member against rearward movement at a time previous to its full outward withdrawal, mechanism actuated by said coin in the slidable member, and vending mechanism conjunctively related to the latter mechanism.

43. A coin - controlled vending - machine comprising starting mechanism including a slidable member having an upper projection, a slotway above the said slidable member and intimately related thereto, an expeller in the slotway, and a trigger engaging the said expeller and adapted to be operated by a projection on the slidable member on the starting mechanism.

44. A coin - controlled vending - machine comprising in its organization starting mechanism including a slidable member with a projection thereon, a slotway above the said slidable member and having an expeller therein with a movable shield thereover, and a trigger below the slotway and in engagement with the expeller and adapted to be operated by the projection on said slidable member to throw up the expeller.

45. A coin - controlled vending - machine having a slidable member with a projection thereon and accorded a limited outward movement before being regularly unlocked, a slotway above the said starting mechanism having a longitudinally-slotted plate therein with an upper roughened surface, a gravitating expeller movable in said slotted plate, and a trigger engaging the said expeller and adapted to be operated by a projection on the slidable member to throw up the expeller and relieve the slotway of slugs, washers or analogous devices.

46. A coin - controlled vending - machine comprising in its organization a starting mechanism including a slidable member having a projection thereon and accorded a limited outward movement previous to a regular release thereof, a slotway disposed above the starting mechanism and having a movable expeller therein with a forwardly-extending projection to move up into the slotway in ad-

vance of the position of said expeller, and a trigger below the slotway adapted to be engaged and operated by the projection on the slidable member and having in operative relation thereto a part of the said expeller, whereby both expeller and projection therefrom may be thrown up to clear different parts of the slotway of irregular obstructions.

47. A coin - controlled vending - machine comprising in its organization starting mechanism including a sliding member with a projection thereon, a slotway in relative position to said starting mechanism and having an expeller gravitatingly mounted therein, an inclined guide with a trough or receptacle at one side in rear of said expeller, and a trigger engaging the expeller and adapted to be operated by the contact therewith of the projection in the slidable member whereby a slug, washer, token or other irregular device may be expelled from the slotway and deposited on the guide and directed into the trough or receptacle.

48. A coin - controlled vending - machine comprising a starting mechanism adapted to receive a regularly-deposited prescribed coin, vending mechanism conjunctively related to the starting mechanism, and a slotway operatively disposed to the starting mechanism and having a drop at the front portion thereof with an opening therein adapted to receive an automatically-operated locking part of the vending mechanism to prevent the entrance of coin when the machine is empty.

49. A coin - controlled vending - machine comprising starting mechanism including a slidable member adapted to convey a regularly-deposited prescribed coin and a starting-lever having a projection, a coin-chute relatively disposed to the said slidable member to receive the coin therefrom, a receiver supporting a tilting table at the lower termination of the said chute, a lever operatively positioned relatively to a part of the said table and adapted to be pressed by the projection of the starting-lever, a throat leading from the said receiver to a box or receptacle, and a registering device on the box or receptacle adapted to receive and be operated by the pressure of the said lever.

50. A coin - controlled vending - machine comprising in its organization a starting mechanism adapted to receive a regularly-deposited prescribed coin, and vending mechanism intimately related thereto and including in its organization a feeding-hopper or analogous device, having a hot-air compartment surrounding the same, and a heater with a flue connected to said compartment.

In testimony whereof I affix my signature in presence of two witnesses.

THOMAS S. WHEATCROFT.
